UNITED STATES PATENT OFFICE.

JOHN SCHUMACHER AND JOSEPH E. SCHUMACHER, OF LOS ANGELES, CALIFORNIA.

PROCESS OF MAKING PLASTER-BOARD AND THE LIKE.

1,176,322.

Specification of Letters Patent.

Patented Mar. 21, 1916.

Application filed April 23, 1915. Serial No. 23,522.

To all whom it may concern:

Be it known that we, JOHN SCHUMACHER and JOSEPH E. SCHUMACHER, both citizens of the United States, residing at Los Angeles, in the county of Los Angeles and State of California, have jointly invented a new and useful Process of Making Plaster-Board and the Like, of which the following is a specification.

16 This invention relates to improved processes of making plaster board for use in building construction. As is well known, such plaster board is usually formed by applying to a strip or sheet of paper or paper board a coating of suitable plastic material which may be of any desired composition, and include as its ingredients plaster, cement or compositions of the same including finely divided materials of various sorts. To a 20 strip or sheet of board so treated or coated a further strip or sheet is then applied, and when the plastic substance has become set the two boards and the plastic substance have become adhered and constitute generally the plaster board product.

In accordance with the present invention the paper is fed in strips or sheets, and the plastic substance is interposed between the same, in a continuous supply, the two strips 33 of paper or paper stock being fed or gaged or governed in the feed so as to properly space the same and provide for the reception between them of a plastic substance. Furthermore, this paper or paper stock is 38 preferably so treated or impregnated with such proper substance or substances, that its permeation by the liquid or semi-liquid plastic substance is retarded, and the soaking or saturation of such strips or sheets by the 43 plastic substance is delayed, permitting the severed portions of the united strips with the plastic material between the same to be handled by stacking or piling the same for further handling or subdivision prior to the 48 setting or drying or hardening of the plastic substance. When this has occurred, the units of the product may be readily handled for such further treatment or subdivision as is desired. It results that such continuous 53 process may be carried on, and the product conveniently and effectively handled in large quantities, and the severed units of the product consisting of the sheets with the plastic substance interposed may be readily

passed over one another to stack the same, 55 which would not be possible or as readily possible if the paper stock or paper was readily permeable to the moisture of the plastic substance. Furthermore this retardation of the soaking or permeation of the 60 paper by the stock causes a gradual distribution of moisture through the paper stock and a gradual expansion of it due to taking up such moisture without tearing or splitting the paper. The units would likewise 65 tend to curl or roll under such quick absorbing action, whereas a retarded action of this nature prevents such absorption. The units having thus been soaked or permeated with moisture uniformly, and having become fully expanded, it results that after the 70 plastic substance has become set and the units become dried out, the product, having thus become stretched or expanded to its limit, will not further stretch or expand or 75 warp or curl should moisture be applied to the same after it has been applied to the wall or walls or put in place. This retardation of the absorbing action in the sheets or strips likewise permits the units to be 80 handled in stacks prior to the setting or drying action, without tearing or splitting, which would occur if a rapid permeation of the paper sheets took place. After the units described have become hardened or set, they 85 are picked up and placed upon a suitable conveyor, being retained upon the same tray upon which they were first stacked in the initial drying process, it being understood that the units are now set although certain 90 slight moisture remains which is removed by the dry kiln process as hereinafter recited. Upon this conveyor, which may be a car or carrier of any suitable type, the units are 95 cut trimmed longitudinally at their side edges, smoothly and uniformly, and the carrier is then advanced to a station at which the units are trimmed transversely at their ends and likewise severed transversely into proper finished lengths. The several result- 100 ant groups or stacks of units are then angled up so as to stand upon their side edges, together with the original tray upon which they first rested, and each of such stacks with the units vertically disposed is then 105 placed upon a separate carrier or car, the units being suitably spaced apart so that complete drying is facilitated, and such com-

plete drying is performed in a suitable dry kiln into which the particular stack is trundled. After such drying the product is entirely finished, and the separate finished units are sent to market.

It is manifest that many kinds and types of apparatus and means, and many various groupings of parts and features may be employed in carrying on the improved process above outlined. Features of one such particular apparatus or group or combination of parts and features is in part disclosed in a companion application by ourselves for Letters Patent, to be filed. In the accompanying drawings such apparatus is disclosed together with additional features employed in carrying on the process which constitutes the present invention.

Without in any manner implying that the carrying on of this process is to be in any way limited to the utilization of any particular mechanism, means or apparatus, we will now describe such apparatus and grouping or assemblage of features and means as exemplified in the accompanying drawings, in which:

Figure 1 is a side elevation, partly in section of certain features of apparatus suitable for carrying out certain steps of the process; Fig. 2 is a plan view of a portion of the showing in Fig. 1 taken on the line a^2-a^2 , Fig. 1. Fig. 3 is an isometric view of a convenient form of means for severing the plaster board into rough lengths; Fig. 4 is a side elevation of apparatus organized for conveniently carrying out certain steps of the process; Fig. 5 is a plan view of the showing in Fig. 4; Fig. 6 is a side elevation of further apparatus which may be used in carrying out certain steps of the process; Fig. 7 is a plan view of the showing in Fig. 6; and Fig. 8 is a fragmentary detail view of a convenient spacer for use in connection with the drying of the plaster board.

Corresponding parts in all the figures are designated by the same reference characters.

The manner of carrying on the improved process constituting this invention, with particular reference to the apparatus and group of features and elements shown in the drawing, will be readily understood from the foregoing description taken in connection with the accompanying drawings and the following statement.

Referring with particularity to the drawing, in Figs. 1, 2 and 3, A designates plastic composition supply means, B designates the composition mixing means thereof, C and D designate, respectively, paper supply rolls, E designates forming or spreading means and F designates advancing means for the plaster board as well as its component parts.

The plastic composition supply means A comprises a hopper 4 mounted upon suitable framework 5 and provided with a spout 6

and a discharge valve 7 whereby the flow of plastic composition a from the hopper may be regulated and controlled, the spout 6 discharging the composition upon the paper supplied from the paper roll C, the point of such discharge being upon the advancing means at the receiving end thereof.

The composition mixing means A, preferably comprises a mixing trough 8 and a rotatable blade bearing shaft 9 from which the trough is suspended, such shaft 9 being journaled at one end as at 9^a in a suitable standard 9^b and journaled at the other end as at 9^c in a standard 9^d, a tight pulley 10 and a loose pulley 11 being provided at the overhanging end 9^e of the shaft 9. A handle 12 is provided on the trough whereby the trough may be turned about the shaft 9 to discharge each batch of mixed composition into the hopper 4. A water supply pipe 13 is provided above the mixing trough.

The paper supply roll C is rotatably mounted upon a shaft 14, the end 14^a and 14^b of such shaft seating in recesses 14^c and 14^d, respectively, in side members of the framework 5. The shaft mounting is in accordance with the usual practice in mounting large rolls of paper; this paper supply roll C is preferably mounted below the level of the upper surface of the advancing means F and at the receiving end thereof.

The paper supply roll D is rotatably mounted upon a suitable shaft 15 the ends of such shaft seating in suitable recesses 15^a in side members of the framework 5; this paper supply roll D is preferably mounted above the advancing means F slightly forward of the hopper 4, adjacent to the receiving end of the advancing means F.

The forming or spreading means E comprises a roller 16 fixed upon a shaft 17, such shaft 17 being journaled at one end in the framework 5 as at 18^a and at the other end of the framework 5 as at 18^b. The roller 16 is positioned slightly above the advancing means F, the interspace between such roller 16 and the upper surface of the advancing means F determining the thickness of the finished plaster board. Adjusting means 16^a are provided so that the desired thickness of plaster board may be produced.

The advancing means F comprises an endless belt 19, rollers 20 and 21 for such belt, and drive means 7 for the rollers and belt. A horizontal extension 5^a of the framework 5 of the apparatus being formed to properly support the belt, rollers and drive means of the advancing means. The extension 5^a of the framework 5 is formed with a smooth table top 22 slightly wider than the plaster board to be formed thereon and adapted to be traversed by the belt 19 in the advance. Vertical supports 22^a for the table top are provided at intervals along its length. The roller 20 is fixedly mounted upon a shaft 130

19 journaled at its ends in adjustable bearings 33, such adjustable bearings being provided at the rearward end of the advancing means and at the sides of the table top 22 and far enough below such table top so that the top of the roller 20 is in alignment with the surface of the table top. The roller 21 is fixedly mounted upon a shaft 24 journaled at its ends in bearings 21, provided at the discharge end of the advancing means 16 and at the end of the table top 22, the roller 21 being positioned so that its top is in alignment with the table top 22.

The drive means *F* comprises a transverse shaft 25 provided with sprockets 26, 27 and 28, a pulley 29, a sprocket 30 and chains 31, 32 and 33, together with a drive motor 34 and its attendant features for speed reduction. The shaft 25 is journaled as at 25^a upon the framework 5, beneath the table top 22, the sprockets 26 and 27 being secured to the shaft 25 at one of its overhanging ends and the sprocket 28 being secured to the shaft 25 at its other overhanging end, the connecting chain 31 being run about the sprocket 27 and the sprocket 29 which is fixed to the shaft 24 of the roller 21. The chain 32 is run about the sprocket 28 and the sprocket 30, the sprocket 30 being fixed to the shaft 28 of the roller 20, and the chain 33 is run about the sprocket 20 and a sprocket 34 comprised within the speed reduction means of the motor. The power *C* from the coil *C* is fed onto the belt 19 above the roller 20 and passes under the depending roller 16, the plastic composition, during the operation of the apparatus, being passed directly onto this paper *c*, guide boards 35 and 36 being provided to assist in the proper distribution of the plastic composition and to confine the same so that it must pass under the roller 16. These guide boards 35 and 36 converge toward the advancing end of the advancing means where they are united by an end board 37. The other ends of the guide boards 35 and 36 are 33^a away as at 35^b to fit the roller 16 and extend slightly beyond the same as at 35^c and 36^c. The paper *d* passes around the roller 16 and during the operation of the apparatus the plastic composition *a* is drawn on the paper *c* to the roller 16 where it passes between such paper *c* and the paper *d*, being allowed to pass under the roller 16 and the paper *d* thereof in an even layer, the projections 35^b and 36^b of the guide boards 35 and 36, respectively, preventing the composition *a* at the sides of the paper *a* and paper *c* and *d* are caused to run under the roller 16.

When it is desired to sever the plaster board being continuously produced by the apparatus, the cutting implement *g*, illustrated in Fig. 8, may be inserted between the plaster board and the belt 19, the cutting

implement being allowed to move along with the belt and still flexible plaster board. The cutting implement *g* comprises a thin strip of wood or the like 38 and a metallic wire 39 one end of which is secured to one end of the wooden strip 38 as at 39^a and the other end of which is provided with a handle 39^b adapted to lie over the similarly shaped handle portion 38^a of the strip, the wire 39 being stretched or straightened out 75 and lying on the strip 38 when the handles 38^a and 39^b are brought together so that they may be held by one hand of the operator while the cutting implement is being inserted beneath the plaster board on the belt 19; after the implement has been passed beneath the plaster board from side to side, the strip 38 is held to the moving conveyor belt and the handle 39^b of the cutting wire 39 is raised so as to force the wire through 85 the still soft and flexible plaster board.

A platform 5^b is provided at a suitable height on the framework 5, to facilitate the charging of the mixer and the handling of the ingredients used in the plastic composition.

Suitable trays or movable platforms *H* are placed at the discharge end of the advancing means *F* to receive the successively severed portions of plaster board delivered 95 by the advancing means, the still flexible and soft plaster board being allowed to set or harden on such trays, each tray being loaded with the successive layers of separate plaster board preferably to the number of 100 fifteen to twenty layers.

Referring now to Figs. 4, 5, 6, 7 and 8, and the apparatus and devices shown therein, *J* designates a traveling crane or the like provided with hoops 40 by means of which 105 the loaded trays *H*, shown also in Figs. 1 and 2, may be handled, and set aside that the plastic composition may set or harden, and the trays with the layers of plaster board thereon otherwise brought into desired 110 positions for the other steps of the process. *K* designates trimming means for the longitudinal trimming of the plaster board strips, *L* designates means for the transverse trimming and severing of the plaster board 115 strips, *M* designates holding and conveying means for the trimmed plaster board sheets and *N* designates a kiln in which the process may be completed. The trays or forms *H* may each consist of a low table 41 provided 120 at one side with removable side boards 42, such side boards being preferably slightly spaced apart as at 42^a and terminating slightly inward of the ends of the table top 41 so that the transverse trimming of the 125 plaster board layers on such tray may be performed as by a swing saw 43 constituting the transverse trimming means *L*.

The longitudinal trimming means *K* may comprise a pair of depending circular saws 130

44 mounted upon a suitable mandrel 45 journaled in a framework 46 and positioned over a track 47 upon which is provided a carrier or wheeled car 48 adapted to successively receive the trays H and convey the same past the saws 44 to trim both edges of the layers of plaster board on the trays H. After such wheeled carrier has passed the longitudinal saws, bearing the respective tray H with its 19 longitudinally trimmed layers of plaster board, the carrier may be stopped at the transverse trimming means L to permit the ends of the plaster board layers to be trimmed and subdivide such layers if desired. The saw 43 of the transverse trimming means L is preferably swung from an overhead framework in the conventional manner by means of a swinging frame 49.

The holding and conveying means M for the drying operation may comprise a wheeled car 50 adapted to run on a suitable track 51 such car 50 being provided with vertical spacing stakes 52 which serve to hold the plaster board layers in vertical position and spaced apart, such stakes being provided at their tops and bottoms, respectively, with spacing blocks 52^a and 52^b the stakes being preferably tapered as at 52^a to fit complementarily formed apertures 50^a in the horizontal car body.

The kiln N may be of standard construction and organization, the track 51 leading from the point of discharge of the carrier 47 where the trimmed plaster boards are transferred to the car 50, into and through the kiln N, such kiln being provided at one end with a vertical sliding door 53 to permit entrance of the loaded car 50, and a vertical sliding door 54 at the other end to permit removal of the loaded car 50, bearing the finished product.

The trays H are so organized that they may be caused to stand on the edge provided with the side boards 42, with the bottom or table of such trays H brought to nearly vertical position, to facilitate the loading of the kiln cars in a proper manner.

Having thus disclosed our invention, we claim and desire to secure by Letters Patent:

1. The herein disclosed process of making plaster board and the like, consisting in feeding and advancing strips of suitable material, supplying moist unstable plastic substance between the same, causing the uniform distribution of the plastic substance between the sheets to a predetermined thickness of layer, subdividing the sheets with the interposed plastic substance into first lengths, in which form they are dried and caused to harden or set, trimming of the same at the edges, reducing the same to final lengths, and finally drying the same.

2. The herein disclosed process of making plaster board and the like, consisting in feeding and advancing strips of suitable ma-

terial, supplying moist unstable plastic substance between the same, causing the uniform distribution of the plastic substance between the sheets to a predetermined thickness of layer, subdividing the sheets with the interposed plastic substance into first lengths, in which form they are dried and caused to harden or set, trimming of the same at the edges, reducing the same to final lengths, and finally drying the same in spaced positions.

3. The herein disclosed process of making plaster board and the like, consisting in feeding and advancing strips of suitable material, supplying moist unstable plastic substance between the same, causing the uniform distribution of the plastic substance between the sheets to a predetermined thickness of layer, subdividing the sheets with the interposed plastic substance into first lengths, in which form they are dried in superposed relation and caused to harden or set, trimming of the same at the edges, reducing the same to final lengths, and finally drying the same.

4. The herein disclosed process of making plaster board and the like, consisting in feeding and advancing strips of suitable material, supplying moist unstable plastic substance between the same, causing the uniform distribution of the plastic substance between the sheets to a predetermined thickness of layer, subdividing the sheets with the interposed plastic substance into first lengths, in which form they are dried in superposed relation and caused to harden or set, trimming of the same at the edges, reducing the same to final lengths, and finally drying the same in spaced positions.

5. The herein disclosed process of making plaster board and the like, consisting in feeding and advancing strips of suitable material treated to retard permeation by moisture, supplying moist unstable plastic substance between the same, causing the uniform distribution of the plastic substance between the sheets to a predetermined thickness of layers, subdividing the sheets with the interposed plastic substance into first lengths, in which form they are dried and caused to harden or set, trimming of the same at the edges, reducing the same to final lengths, and finally drying the same.

6. The herein disclosed process of making plaster board and the like, consisting in feeding and advancing strips of suitable material treated to retard permeation by moisture, supplying moist unstable plastic substance between the same, causing the uniform distribution of the plastic substance between the sheets to a predetermined thickness of layer, subdividing the sheets with the interposed plastic substance into first lengths, and trimming the same in spaced positions.

7. The herein disclosed process of making plaster board and the like, consisting in feeding and advancing a strip of suitable material treated to retard permeation by moisture, supplying moist unstable plastic substance upon the strip, advancing the strip and the plastic substance thereon to unite the same with another strip treated to retard permeation by moisture, causing the uniform distribution of the plastic substance between the sheets to a predetermined thickness of layer, subdividing the sheets with the interposed plastic substance into suitable lengths, and stacking the same in superficial contact.
8. The herein disclosed process of making plaster-board and the like consisting in uniting with a sheet of paper or the like in superficial contact therewith, said sheet of paper or the like being treated to retard permeation by moisture, a moist unstable plastic substance and under pressure, gradually hardening the plastic substance during the retarded permeation of the paper or the like
- by the moisture of the plastic substance, and finally dry-finishing the same.
9. The herein described process of making plaster-board and the like, consisting in uniting with two sheets of paper or the like in superficial contact therewith, said sheets of paper or the like being treated to retard permeation by moisture, a moist unstable plastic substance interposed between such sheets of paper or the like and under pressure, gradually hardening the plastic substance during the retarded permeation of the paper or the like by the moisture of the plastic substance, and finally dry-finishing the same.
- In testimony whereof, we have signed our names to this specification in the presence of two subscribing witnesses.

JOHN SCHUMACHER.
